FIREARM

David M. Williams, New Haven, Conn., assignor to
 Western Cartridge Company, New Haven,
 Conn., a corporation of Delaware

Application October 26, 1940, Serial No. 362,941
 In Canada October 7, 1940

5 Claims. (Cl. 42—20)

The present invention relates to improvements in firearms, and more particularly to improvements in firearms of the type wherein a receiver and a trigger-plate unit are separable one from the other.

One of the objects of the present invention is to provide a superior firearm-structure wherein a trigger-plate unit and a receiver are organized together in a simple, reliable and effective manner with capacity for ready separation.

Another object of the present invention is to provide a superior firearm-structure embodying separable receiver and trigger-plate units and in which the tension of a firing-spring may be utilized for minimizing vibration between the two said units when the same are assembled together.

A further object of the present invention is to provide a superior firearm-structure wherein a firing-spring is so related to the separable receiver and trigger-plate units as to act to facilitate the separation of the said units.

Still another object of the present invention is to provide a superior firearm-structure wherein a firing-spring is organized with a trigger-plate unit so as to be handleable as a part thereof and which firing-spring is automatically tensioned and untensioned respectively by the attachment to and the removal of the said trigger-plate unit with respect to a receiver-unit.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken view mainly in side elevation and partly in vertical central-longitudinal section of a portion of a firearm-structure in which the present invention is embodied;

Fig. 2 is an underside view thereof;

Fig. 3 is a transverse sectional view taken on the line 3—3 of Fig. 1;

Fig. 4 is a similar view taken on the line 4—4 of Fig. 1;

Fig. 5 is a transverse sectional view taken on the line 5—5 of Fig. 1;

Fig. 6 is a view substantially corresponding to Fig. 1, but showing the trigger-plate unit moved forwardly relative to the receiver-unit under the urge of the firing-spring, preparatory to the

complete removal of the said trigger-plate unit from the said receiver-unit;

Fig. 7 is a view in side elevation of the receiver-unit detached, together with a portion of the barrel;

Fig. 8 is an underside view thereof;

Fig. 9 is a view in side elevation of the trigger-plate unit, detached; and

Fig. 10 is a top or plan view thereof.

10 The particular firearm-structure herein chosen for the purpose of illustrating the present invention includes a receiver 20 from the forward end of which rigidly extends a barrel 21. Located mainly below the receiver 20 and demountably attached thereto in a manner as will hereinafter appear, is a trigger-plate unit generally designated by the reference character 22.

The receiver 20 includes a top wall 23 and two laterally-spaced-apart side walls 24 and 25 integral with and extending downwardly from the said top wall 23. The top wall 23 together with the side walls 24 and 25 of the receiver 20 provide in the said receiver a downwardly-opening mechanism-receiving chamber 26.

25 The mechanism-receiving chamber 26 above referred to accommodates a breech-bolt 27 as well as other features of the firearm not requiring illustration or description herein. As indicated in Fig. 1, the breech-bolt 27 has the rear 20 end of a firing-plunger 28 projecting through its rear face for engagement by a hammer in a manner as will hereinafter appear.

At its rear end, the receiver 20 is formed with an integral depending-arm 29 having a guide-25 passage 30 extending longitudinally of the receiver in a slightly upwardly and forwardly inclined direction. The said guide-passage 30 is generally of cylindrical form save that on each of its respective opposite sides, it is formed with 40 one of two groove-like lateral extensions 31—31 as is especially well shown in Fig. 3, and for purposes as will more fully hereinafter appear.

About midway of its length the receiver 30 is formed with two opposed coupling-ribs 32 and 45 33 respectively formed integral with and extending inwardly from the complementary side walls 24 and 25 of the receiver 20 adjacent the lower edge thereof. The said coupling-ribs 32 and 33 slope slightly forwardly and upwardly in conformity with the slope of the under edges of the side walls 24 and 25.

At its forward end and adjacent the barrel 21, the receiver 20 is formed with an integral depending coupling-lug 34 which is formed at its lower end with a coupling-head 35. The said

coupling-head 35 is of substantially-T-shaped form in cross section and is provided on each of its respective opposite sides with one of two coupling-ribs 36 and 37 spaced downwardly from the under face of the coupling-lug 34 proper and extending longitudinally of the firearm on a slope conforming to the slope of the under edge of the side walls 24 and 25 of the receiver 20.

Extending substantially vertically in the coupling-lug 34 and its coupling-head 35 is a 10 downwardly-opening cylindrical pocket 38 in which is adapted to reciprocate a locking-plunger 39 which is urged downwardly by a helical locking-spring 40, as is shown particularly well in Fig. 5. As is shown especially well in Fig. 1, the rear face of the locking-plunger 39 is formed with a transverse limiting-groove 41 receiving substantially one-half of the diameter of the central portion of a limiting-pin 42 extending transversely across and carried by the coupling-lug 34 before referred to. The said limiting-groove 41 in the locking-plunger 39 is so positioned that its upper end engages with the limiting-pin 42 when the said locking-plunger is at the limit of its desired downward travel, so that the said locking-plunger is prevented from becoming separated from the receiver-unit when the trigger-plate unit 22 is removed therefrom, in a manner as will hereinafter appear.

The locking-plunger 39 above referred to is formed at its lower end with a conically-contoured locking-nose 43 which under normal circumstances is seated in a conically-contoured locking-socket 44 formed substantially vertically in the front crosshead 45 of the trigger-plate unit 22 before referred to. In its upper face, the front crosshead 45 of the trigger-plate unit 22 is formed with a longitudinal coupling-groove 46 of T-shaped form in cross section and having on each of its respective opposite sides one of two coupling-ribs 47 and 48 which extend laterally toward each other. The said coupling-ribs 47 and 48 extend substantially longitudinally of the firearm-structure on a slope conforming to the slope of the under edges of the side walls 24 and 25 of the receiver 20, and as is shown particularly well in Fig. 5 the said coupling-lugs are spaced upwardly above the bottom of the coupling-groove 46. The coupling-ribs 47 and 48 are thus positioned to respectively fit over the coupling-ribs 36 and 37 of the coupling-head 35 at the lower end of the coupling-lug 34 of the receiver 20. The fit between the coupling-ribs 36 and 37 on one hand and the coupling-ribs 47 and 48 on the other hand is such that when the locking-plunger 39 is retired in a manner as will hereinafter appear, the trigger-plate unit 22 may be slid longitudinally with respect to the receiver 20.

Extending rigidly rearwardly from the front crosshead 45 of the trigger-plate unit 22 are two laterally-spaced-apart parallel side-bars 49 and 50 joined together at a point substantially midway the length of the trigger-plate unit by a rear cross-head 51. The said crosshead 51 is provided with an upwardly-projecting integral coupling-lug 52 extending upwardly into the open lower portion of the mechanism-receiving chamber 26 in the receiver 20, as is shown especially well in Fig. 4. On each of its respective opposite sides, the coupling-lug 52 is formed with one of two parallel grooves 53 and 54 respectively receiving the coupling-ribs 32 and 33 respectively formed at the lower ends of the side walls 24 and 25 of the receiver 20, as before described. The

formation of the coupling-grooves 53 and 54 just referred to results in the formation at the respective opposite sides of the coupling-lug 52 and adjacent the upper end thereof, of two coupling-ribs 55 and 56 respectively resting upon the upper surfaces of the coupling-ribs 32 and 33 of the receiver 20, as is especially well shown in Fig. 4.

Formed integral with and projecting rearwardly from the rear crosshead 51 of the trigger-plate unit 22, is a trigger-plate proper 57 having a central-longitudinal groove-like recess 58 in its upper face which recess is intersected by a clearance-passage 59 extending downwardly from the said recess into the interior of the space defined by a loop-like trigger-guard 60 forming an integral part of the trigger-plate proper 57.

Mounted for swinging movement in the recess 58 and the clearance-passage 59 of the trigger-plate proper 57 is a trigger 61 having a finger-piece 62 located within the space enclosed by the trigger-guard 60, as is shown in the drawings. The said trigger 61 is mounted for pivotal movement upon a pivot-pin 63 extending transversely across and carried by the trigger-plate proper 57. The trigger 61 is also provided with a rigid forwardly-projecting sear-arm 64, between the under face of which and the bottom of the groove-like recess 58 is interposed a helical trigger-spring 65 which exerts a constant effort to swing the trigger 61 in a counterclockwise direction.

The sear-arm 64 of the trigger 61 is provided with a forwardly-facing cocking-abutment 66 which is adapted to releasably engage with a 35 cocking-abutment 67 formed upon a pivotal hammer 68 adjacent the lower end thereof. The said hammer is pivoted upon a pivot-pin 69 extending through the said hammer and supported at its respective opposite ends in the trigger-plate proper 57.

Pivots connected to the hammer 68 by means of a pivot-pin 70 is the bifurcated forward end of a hammer-actuating plunger 71 which is formed at its forward end with a deep vertical-longitudinal notch 72 in which the hammer 68 is received.

The hammer-actuating plunger 71 extends substantially horizontally at a slight downward and rearward inclination and is provided at its 50 rear end with a cylindrically-contoured stem 73 extending at its rear with a free sliding fit into the guide-passage 30 in the lower end of the arm 29 at the rear end of the receiver 20. Encircling the stem 73 of the hammer-actuating plunger 71 is a helical firing-spring 74 which thrusts at its rear end against the forward face of the arm 29 of the receiver 20 and which at its 55 forward end thrusts against a rearwardly-facing spring-seat 75 formed on the said plunger 71 at the point of junction of its stem 73 with the larger size forward portion of the plunger, as is especially well shown in Figs. 1, 2, 6, 9 and 10.

To prevent the firing-spring 74 from unintentionally coming off of the rear end of the stem 73 of the hammer-actuating plunger 71 when the trigger-plate unit 22 is demounted from the receiver 20 in a manner as will hereinafter appear, the said stem 73 is provided at its rear end with a transverse spring-retaining pin 76 which projects outwardly from each of the respective opposite sides of the said stem. Clearance for the said spring-retaining pin 76 is provided by the groove-like extension 31—31 of the

guide-passage 30 in the arm 29 of the receiver 20, as is especially well shown in Fig. 3.

As the parts are thus constructed and arranged, the firing-spring 74 tends to move the receiver 20 rearwardly with respect to the trigger-plate unit 22 by thrusting upon the arm 29 of the receiver 20. The said firing-spring 74, by virtue of its forward thrust upon the hammer-actuating plunger 71, acts through the intermediary of the pivot-pin 70, hammer 68 and pivot-pin 69 to tend to force the trigger-plate unit 22 forwardly relative to the receiver 20.

The above-referred to thrusts of the firing-spring 74 are normally prevented from being effective in shifting the receiver 20 and trigger-plate unit 22 relative to each other by the releasable locking-plunger 39.

When it is desired to discharge the firearm, a rearward draft exerted upon the finger-piece 62 of the trigger 61 will serve to turn the said trigger in a clockwise direction to thus depress its sear-arm 64 and hence disengage the cocking-abutment 66 of the said sear-arm from the cocking-abutment 67 of the hammer 68.

As soon as the cocking-abutment 66 is disengaged from the cocking-abutment 67, as above described, the hammer 68 will be released and will swing in a clockwise direction at a very rapid rate under the urge of the firing-spring 74 acting through the intermediary of the hammer-actuating plunger 71. Under the conditions just described, the front edge of the upper portion of the hammer 68 will strike the exposed rear end of the firing-plunger 28 and in a manner well known in the art will effect the discharge of the firearm.

The hammer 68 may be re-cocked by any suitable means not requiring either illustration or description herein.

Should it be desired to demount the trigger-plate unit 22 from the receiver 20, such demounting may be effected by thrusting upwardly upon the exposed lower end of the locking-plunger 39 to retire the said locking-plunger upwardly until the under face of its locking-nose 43 is retired to a point above the top of the conical locking-socket 44 in the front crosshead 45 of the trigger-plate unit 22. The described upward retirement of the locking-plunger 39 may be conveniently effected by inserting the point of a cartridge upwardly through the open lower end of the locking-socket 44.

As soon as the under face of the locking-nose 43 of the locking-plunger 39 is clear of the locking-socket 44, as above described, the firing-spring 74 will assert itself and thrust the entire trigger-plate unit 22 and the parts carried thereby forwardly into substantially the positions in which they are shown in Fig. 6. At this time the spring-retaining pin 76 at the rear of the hammer-actuating plunger 71 will move forwardly with the said plunger and engage with the rear end of the firing-spring 74 and thus prevent any further axial expansion of the latter.

It is preferred to so proportion the parts that the hammer-actuating spring 74 will not move the trigger-plate unit 22 forwardly to a degree sufficiently to completely disengage the coupling-ribs 47 and 48 thereof from the coupling-ribs 36 and 37 of the coupling-lug 34 of the receiver 20. The degree of movement just referred to will, however, be sufficient to move the coupling-ribs 55 and 56 on the coupling-lug 52 forwardly out of engagement with the coupling-ribs 32 and 33 on the receiver 20 as is shown in Fig. 6. It is

therefore preferred that the parts be moved by the firing-spring 74 only into substantially the positions in which they are shown in Fig. 6.

After the parts have assumed the positions in which they are shown in Fig. 6, a slight additional forward movement manually imparted to the trigger-plate unit 22 will completely separate the latter from the receiver 20, and carried along as an assembly with the said trigger-plate unit will be the trigger 61, hammer 68, hammer-actuating plunger 71 and firing-spring 74, as is shown especially well in Figs. 9 and 10.

Should it be desired, as may be the case under some conditions, the trigger-plate unit 22 and the parts carried thereby may be demounted from the receiver 20 by first releasing the locking-plunger 39 as before described, and then thrusting rearwardly upon the trigger-plate unit 22 to overcome the tension of the firing-spring 74 and so disconnecting the front crosshead 45 from the coupling-lug 34 and disconnecting the coupling-lug 52 from the intermediate portion of the receiver 20.

To reassemble the receiver 20 and trigger-plate unit 22, the parts may be first reassembled so that they assume the positions in which they are shown in Fig. 6, after which the locking-plunger 39 should be upwardly retired and then the trigger-plate unit may be manually forced rearwardly relative to the receiver 20. When during the rearward movement of the trigger-plate unit 22 the locking-socket 44 in the forward end of the latter is brought into registration with the locking-nose 43 of the locking-plunger 39, the latter will snap downwardly under the urge of the locking-spring 40 and re-enter the said locking-socket 44 to the full extent when the parts have been moved into the relative positions in which they are shown especially well in Fig. 1.

When the trigger-plate unit 22 and receiver 20 are assembled together, the firing-spring 74 not only serves to actuate the hammer 68, but also serves to minimize vibration between the said receiver 20 and trigger-plate unit 22. Furthermore, the said firing-spring 74 may be utilized to facilitate the demounting of the trigger-plate unit 22 from the receiver 20 in a manner as has been above described.

By terminating the trigger-plate unit 22 short of the rear end of the receiver 20 and causing the hammer-actuating plunger 71, or its equivalent, to "bridge over," so to speak, between the two said elements, it is possible to minimize the weight of the assembly and, at the same time, avoid the need for too deeply cutting away such a stock as may be applied to the firearm. The construction and arrangement of parts as shown by avoiding the necessity for too deeply cutting away the material of a stock enables the said stock to be materially strengthened at the critical point adjacent the rear end of the receiver 20.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A firearm-structure including in combination: a receiver; a trigger-plate unit adjacent the said receiver and removable therefrom by a for-

ward movement with respect thereto; coupling-means for holding the said receiver and the said trigger-plate unit against lateral separation and constructed and arranged to be releasable by a relative forward movement of the said trigger-plate unit with respect to the said receiver; a firing-mechanism organized with the said trigger-plate unit so as to be demountable therewith from the said receiver; a firing-spring for actuating the said firing-mechanism and thrusting rearwardly against the said receiver to urge the same rearwardly with respect to the said trigger-plate unit, the said firing-spring also thrusting forwardly against the said trigger-plate unit to urge the same forwardly with respect to the said receiver to release the aforesaid coupling-means; and locking-means normally releasably holding the said trigger-plate unit against forward movement with respect to the said receiver.

2. A firearm-structure including in combination: a receiver; a trigger-plate unit adjacent the said receiver and removable therefrom by a forward movement with respect thereto; coupling-means for holding the said receiver and the said trigger-plate unit against lateral separation and constructed and arranged to be releasable by a relative forward movement of the said trigger-plate unit with respect to the said receiver; a firing-mechanism organized with the said trigger-plate unit so as to be demountable therewith from the said receiver; a firing-spring for actuating the said firing-mechanism and thrusting rearwardly against the said receiver to urge the same rearwardly with respect to the said trigger-plate unit, the said firing-spring also thrusting forwardly against the said trigger-plate unit to urge the same forwardly with respect to the said receiver to release the aforesaid coupling-means; locking-means normally releasably holding the said trigger-plate unit against forward movement with respect to the said receiver, and retaining-means for retaining the said firing-spring in organized relationship to the said trigger-plate unit when the latter is separated from the said receiver.

3. A firearm-structure including in combination: a receiver having a depending arm adjacent its rear end; a trigger-plate unit adjacent the said receiver and located forwardly of the depending arm thereof; coupling-means holding the said receiver and the said trigger-plate unit against lateral separation and constructed and arranged to be releasable by a relative forward movement of the said trigger-plate unit with respect to the said receiver; a firing-mechanism organized with the said trigger-plate unit so as to be demountable therewith from the said receiver and also located forwardly of the depending arm of the said receiver; a firing-spring for actuating the said firing-mechanism and thrusting simultaneously rearwardly against the depending arm of the said receiver and forwardly against the said trigger-plate unit to release the aforesaid coupling-means; and locking-means

normally releasably holding the said trigger-plate unit against forward movement with respect to the said receiver.

4. A firearm-structure including in combination: a receiver having a depending arm adjacent its rear end; a trigger-plate unit adjacent the said receiver and located forwardly of the depending arm thereof; coupling-means for holding the said receiver and the said trigger-plate unit against lateral separation and constructed and arranged to be releasable by a relative forward movement of the said trigger-plate unit with respect to the said receiver; a firing-mechanism organized with the said trigger-plate unit so as to be demountable therewith from the said receiver and also located forwardly of the depending arm of the said receiver; a firing-spring for actuating the said firing-mechanism and thrusting simultaneously rearwardly against the depending arm of the said receiver and forwardly against the said trigger-plate unit to release the aforesaid coupling-means; locking-means normally releasably holding the said trigger-plate unit against forward movement with respect to the said receiver; and retaining-means for retaining the said firing-spring in organized relationship to the said trigger-plate unit when the latter is separated from the said receiver by a relative forward movement with respect thereto.

5. A firearm-structure including in combination: a receiver having a depending arm adjacent its rear end, the said arm being formed with a guide-passage; a trigger-plate unit removably secured to the said receiver and located forwardly of the depending arm thereof; coupling-means for holding the said receiver and the said trigger-plate unit against lateral separation and constructed and arranged to be releasable by a relative forward movement of the said trigger-plate unit with respect to the said receiver; a hammer pivoted to the said trigger-plate unit; a sear also pivoted to the said trigger-plate unit and coacting with the said hammer to releasably hold the same in its cocked position; a hammer-actuating plunger pivoted adjacent its forward end to the said hammer and having a rear portion reciprocatable in the guide-passage in the depending arm of the said receiver; a firing-spring mounted upon the said hammer-actuating plunger and simultaneously thrusting forwardly thereon and rearwardly against the depending arm of the said receiver; spring-retaining means carried by the said hammer-actuating plunger adjacent the rear end thereof to retain the said firing-spring on the said hammer-actuating plunger when the said trigger-plate unit, together with the parts pivoted thereto, is demounted from the said receiver; and locking-means normally releasably holding the said trigger-plate unit against forward movement with respect to the said receiver.

DAVID M. WILLIAMS.
